UNITED STATES PATENT OFFICE.

WILLIAM VOGLER, OF SOMERVILLE, MASSACHUSETTS, ASSIGNOR OF ONE-HALF TO GEORGE N. PHELPS, OF BOSTON, MASSACHUSETTS.

UPHOLSTERED FURNITURE.

SPECIFICATION forming part of Letters Patent No. 661,829, dated November 13, 1900.

Application filed July 16, 1900. Serial No. 23,698. (No model.)

To all whom it may concern:

Be it known that I, WILLIAM VOGLER, a citizen of the United States, and a resident of West Somerville, county of Middlesex, State of Massachusetts, have invented an Improvement in Upholstered Furniture, of which the following description, in connection with the accompanying drawings, is a specification, like characters on the drawings representing like parts.

This invention relates to upholstered furniture; and it has for its object the production of sanitary furniture of this class—that is, upholstered furniture—in which there is no chance for vermin to lodge in the frame. I accomplish this object by making the frame of the article of furniture of pieces of angle-iron suitably riveted together to form the required shape, said frame being supported by suitable legs, and to enable the covering or upholstery to be attached to such metal frame I permanently attach to it an exposed nailing-strip of any suitable wood—such as cherry, mahogany, or other wood—which may be carved or otherwise ornamented, as desired, said nailing-strip being provided with a shoulder located at a distance from its lower edge, which shoulder receives against it the edge of the upholstery, said upholstery being secured in place by tacks or other suitable means. A line of gimp is suitably secured to the nailing-strip along the line of junction of the said strip and the edge of the upholstery, thus giving a finish to the completed article, which in this embodiment of my invention is shown as a lounge.

The legs of the article of furniture are preferably made of the same kind of wood as the nailing-strip and are similarly ornamented.

Figure 1 of the drawings shows in plan view the frame of an article of furniture made in accordance with my invention without the upholstery. Fig. 2 is a side elevation showing the rabbeted nailing-strip, said nailing-strip being partially broken away to show the manner of attaching it to the metal frame. Fig. 3 is a cross-section of the nailing-strip and frame, taken on the line $y-y$, Fig. 1, and showing the manner of attaching the upholstery

and gimp to the nailing-strip; and Fig. 4 is a detail showing the manner of attaching the legs to the metal frame.

In the production of furniture in accordance with my invention I take angle-iron and cut it into proper lengths, which are suitably secured together, preferably by riveting, to form the frame of the particular article I am constructing. As illustrating one embodiment of my invention I have chosen a lounge, and my invention will be hereinafter described with particular reference to this article of furniture, though I wish it understood that the invention is not limited to lounges, but may be employed in the manufacture of other pieces of upholstered furniture.

In making a lounge I take pieces of angle-iron a of suitable lengths for the ends of the lounge and other pieces b of suitable lengths for the sides, and these pieces are secured together and to the legs 2 of the lounge to form the frame as follows: The outer sides of each leg have horizontal grooves 3 and 4 , which are adapted to receive the horizontal portions of the angle-iron pieces a and b , as shown in Fig. 4, the groove 3 being preferably in a slightly-higher plane than groove 4 , so that when the angle-irons are in place the end of piece a will rest on the end of the horizontal portion of b . (See Fig. 4.) The ends of the pieces a and b are suitably secured together, preferably by riveting, as at 5 , and the faces of the legs are preferably recessed slightly, as at 6 , to receive the vertical portions of the angle-iron pieces a and b , so that the front of the said pieces a and b will be brought flush with the face of the leg. To further strengthen the frame of the lounge, I connect the pieces b by cross-pieces of metal, as c , and the pieces a by similar cross-pieces d and unite the end and side pieces a and b by means of suitable ties e , which may be secured to the pieces a and b in any desired manner, preferably by riveting. When thus constructed, the frame of the lounge is made entirely of metal, is strong and rigid, and yet is extremely light.

If the lounge is to have a headpiece, I pivot to the pieces b and d at f suitable bars g ,

which are connected at their ends in any suitable way by the bar *h*, said bar *h* being preferably riveted to the bars *g*, so as to form a rigid head-frame. The head-frame has secured to its sides suitable brackets or ears 8, to which are loosely pivoted, at 9, suitable pawls or struts 10, the lower ends of which are free to be moved so as to occupy any desired position on a suitable catch or ratchet-plate 12, said ratchet-plate preferably being located inside of the leg 2 and secured to the angle-irons *a* and *b* by any suitable securing means.

The upholstery to be connected with the lounge, which consists, preferably, of a thin quilted covering and an outside cover of any suitable material, will be laid upon and sustained by suitable wire springs, such as represented in Patent No. 562,940, dated June 30, 1896, granted to me, or No. 584,922, dated June 22, 1897, granted to Alexander Y. Cochrane, such springs taking the place of ordinary hair, tow, &c., usually employed in upholstering.

25 In order to provide means for securing the upholstery in place, I have attached to the metal frame thus far described and surrounding the same strips of wood 35, the wood varying in kind and ornamentation according to the price to be asked for the piece of furniture, the said strips, which I will call "nailing-strips," being secured to the outer sides of the angle-irons *a* and *b* by suitable screws 36, (best seen in Fig. 3,) the screws being inserted through the angle-irons from the inside, so that they are not exposed at the face of the nailing-strips 35. The nailing-strips 35 are rabbeted at a distance from their lower edges 38 to leave shoulders 39, as shown in Figs. 2 and 3, against which the covering 40 for the lounge is laid, said covering being connected with the nailing-strip by means of suitable tacks 41. The shoulder 39 will follow the contour of the nailing-strip, as shown in Fig. 2, said contour varying according to the ornamentation of the nailing-strip, and said strips are preferably made wider at their ends where they cover the legs in order to give a more ornamental appearance to the 50 article.

The strips and legs may be carved or ornamented in any other desired way.

The edge of the covering having been tacked against the shoulders 39 on the nailing-strip, a suitable gimp, as 45, is applied along the line of the shoulder 39 and is tacked thereto. (See Fig. 3.)

A lounge constructed as described presents to the eye a wooden frame which may be more or less ornamental, as desired, and a covering of any desired material, and the construction is such that in case of necessity the covering may be readily removed by removing the gimp and withdrawing the tacks 41. The 65 lounge is also a sanitary one, owing to the de-

scribed construction of the frame, as there is no chance for vermin to lodge in the frame, and it is stronger, more desirable, and of lighter weight than any strong wooden-frame lounge.

Prior to my invention I am not aware that an article of furniture having its frame composed wholly of metal has ever had connected therewith permanently a wooden or other nailing-strip to receive tacks employed to hold the covering or upholstery in position on the frame, and hence I wish it understood that my invention is not limited to a lounge constructed as shown, but extends to any article of furniture which comprises a metal frame having permanently attached thereto a wooden strip or strips to receive the tacks employed to secure the covering in position.

Having described my invention, what I claim as new, and desire to secure by Letters Patent, is—

1. An article of furniture, having its body or frame composed of metal, said frame having fixedly attached to it a wooden strip provided externally with a shoulder located above its lower edge, the portion of the strip above the shoulder receiving against it the covering, and being connected therewith by suitable tacks.

2. In an article of furniture, a body or frame composed of angle-iron, wooden legs secured to the frame at each corner, wooden nailing-strips fixedly attached to the metal frame, said nailing-strips each having a shoulder for receiving against it the covering, and means for securing the covering to the nailing-strips.

3. In an article of furniture, a body or frame composed of angle-iron, wooden legs for supporting said frame, said legs having on their outer faces grooves to receive the angle-iron, and wooden nailing-strips attached to the frame, said nailing-strips having a receiving portion for the covering, and means for securing the covering thereto.

4. In an article of furniture, a frame or body composed of angle-iron, wooden legs for supporting said frame, each leg having grooves on two of its faces for the reception of a portion of the angle iron-frame, one of said grooves being located at a higher level than the other, wooden nailing-strips attached to the metal frame, each nailing-strip having a portion adapted to receive the covering, and means to secure the covering to said strips.

5. An article of furniture having its body or frame composed of angle-iron, and its legs made of wood, said legs each having grooves for the reception of the angle-iron frame, and said frame having fixedly attached to it a wooden strip provided externally with a shoulder located above its lower edge, the portion of said strip above said shoulder receiving against it the covering and being connected therewith by suitable tacks.

6. An article of furniture having its body

or frame composed of angle-iron, and its legs made of wood, said legs each having horizontal grooves for the reception of the horizontal portion of the angle-iron frame, one of said 5 grooves being at a higher level than the other, and said frame having fixedly attached to it a wooden nailing-strip provided with a shoulder located above its lower edge, the portion of the strip above the shoulder receiving

against it the covering and being connected to therewith by suitable tacks.

In testimony whereof I have signed my name to this specification in the presence of two subscribing witnesses.

WILLIAM VOGLER.
